UNITED STATES PATENT OFFICE.

HERMAN A. UNKE, OF CLEVELAND, OHIO.

METHOD OF FORMING BEADED ARTICLES.

Application filed September 15, 1926. Serial No. 135,544.

This invention relates to protectors for the threads of pipes and other threaded articles for the purpose of preventing them from being mutilated while the pipe or article is being handled or transported to its point of ultimate use. While the method of making the thread protector is described with particular reference to articles of this kind, the method relates generally to the formation 10 of a bead or groove in a pressed metal tubular article.

An object of the invention is to provide an improved method of forming such bead or groove in thread protectors or other tubular articles that will produce such bead or groove in connection with the drawing operation of forming the article and without requiring an additional step, thereby producing the bead or groove at practically no additional expense over the cost of drawing the article.

A further object of the invention is to provide a method for forming the bead or groove that will result in hardening and stiffening 25 the portion of the article in which the bead is located so that it will be better adapted to retain the form of the article, and also, in the case of thread protectors, to be better adapted to secure the protector in position 30 on the threads.

Other objects of the invention and the features of novelty will be apparent from the following description taken in connection with the accompanying drawings, of which

Fig. 1 is a vertical section through a portion of a stamping press having dies therein that are adapted to form thread protectors and other articles in accordance with my invention;

Fig. 2 is a vertical section of the same at right angles to the section of Fig. 1 and being on the line 2—2 of Fig. 1;

Fig. 3 is a bottom plan of the upper die, the section being on the line 3—3 of Fig. 1;

Fig. 4 is a plan of the bottom die as seen from the line 4—4 of Fig. 1;

Fig. 5 is an enlargement of a part of Fig. 2, with the dies shown in the position they occupy at the beginning of the forming operation of the article;

Fig. 6 is a view similar to Fig. 5 but showing the dies in about the middle position of the forming operations.

Fig. 7 is a view similar to Fig. 5 but showing the dies in the position just preceding 55 the completion of the article;

Fig. 8 shows the dies at the end of their forming stroke, with the completed article therein;

Fig. 9 is a side elevation, partly in section, 60 of a thread protector embodying my invention;

Fig. 10 is a side elevation of the end of a piece of pipe with the thread protector thereon, a portion of the pipe and the protector 65 being shown in section;

Fig. 11 is an elevation of the protector, as seen from the beaded end thereof; and

Fig. 12 is a view similar to Fig. 11 but showing a slightly modified form of construction.

Referring to Figs. 9, 10 and 11, it will be seen that the protector consists of a tubular shell 20 which is adapted to surround the threads 21 of the pipe 22, and has an inwardly turned flange 23 at its outer end and an inwardly extending circumferential bead 24 at its other end. The beaded end of the protector is preferably of non-annular form, and, as will be seen from Fig. 11, may be 80

made oval in form, the true circle being shown in dotted lines at 25. When the protector is forced over the threads 21, the oval shape of the beaded end will be distorted to more nearly circular form, and, because the 85

structure has a certain amount of resiliency, opposite portions of the bead, on the shortest diameter of the oval, will enter the space between successive threads and lock the protector in position. At the same time the 90

flange 23 will engage with the end of the pipe and form a substantial seal at this point that will be adapted to exclude the materials that are used in the coating operations in making conduit and in galvanizing. The 95

bead 24 also has substantial sealing connection with the threads that will exclude objectionable quantities of the coating material. A factor which assists in excluding the coating material is that a certain amount 100

of air is trapped within the shell 20 and this air remains therein during the coating operations. The coating material used for conduit is very thick and viscous, and, therefore, 5 will not penetrate the relatively small spaces between the bead 24 and the threads and between the flange 23 and the end of the pipe.

When the protector is used in connection 10 with the process of galvanizing pipe, a certain amount of the galvanizing material will penetrate the interior of the shell 20 and adhere to the threads that are covered thereby, but the amount of the coating material that will adhere to the threads is 15 relatively small and not objectionable. At the same time, it has sufficient rust-proofing qualities to prevent rusting of the threads while the pipe is in storage or in transit.

In the form of protector illustrated in 20 Fig. 12, the beaded end 24 is slightly flattened at several points, as indicated at the three points 26.

Referring now to Figs. 1 to 8, the method 25 of forming the thread protector will be described. In a general way this method is that commonly employed in the stamping of cup-shaped articles from sheet metal. The method, however, departs from the usual method in several important particulars 30 in order to form the bead in the article and also for the purpose of hardening and stiffening the portion of the article which contains the bead.

A portion of the frame of an ordinary 35 stamping press is shown at 27, and the usual bed-plate at 28. The ram of the press is indicated at 29 and is slidable on the guides or ways 30. The ram 29 is reciprocated by a mechanism forming no part 40 of the present invention and not illustrated in the drawings. The body 31 of one of the die members is secured to the ram 29 by means of the clamp 32 and bolts 33. The female forming die is indicated at 34 and 45 is secured to the body 31 by screws 35. The base of the other die is shown at 36 and is secured on the bedplate 28 by the bolts 37. The base 36 carries a plurality of parallel extending guides 38 which project through the 50 body member 31 and thus hold the two parts of the die in accurate alignment. The male forming die is shown at 39 and is carried by the base 36. It is provided with a tapered bore 40 and its upper end is adapted to 55 operate with a punch 41, which, as shown in Figs. 2 and 6, is adapted to punch out the disk 42 from the end of the article.

A vertically movable collar 43 surrounds 60 the male forming die 39 and slides in a cavity 44 of the female blanking die 45, the latter being positioned on the base 36.

The bore 46 of the die 34 conforms to 65 the desired shape and size of the outer surface of the article to be formed, and, at the lower end of the bore 46, the die 34 has a

well rounded corner 47 over which the metal of the blank is drawn in forming the article. The outer lower corner 48, of the die 34, cooperates with the die 45 to punch out the blank from the strip of metal 69 that 70 constitutes the raw material that is fed to the press. Within the die 34 there is a 75 slideable knock-out member 49 which surrounds the punch 41 and guides the latter, and the lower end 50 of which is adapted to engage the article, on the upward stroke of the press, and knock it out of the die 34.

A plurality of rods 51 extend through the base 36 and the bed-plate 28 and have their upper ends in engagement with the collar 43 and their lower ends in engagement with a disk 52, which is slideable on a rod 53 that has its upper end threaded into a bracket 54 that is secured to the underside of the base 36 by means of bolts 55. The bracket 54 has a slot 56 that is in alignment with the bore 40 of the die 39, and the disks 42 are discharged through this slot. The lower end of the rod 53 is threaded to receive an adjusting nut 57 which supports 80 a collar 58. A spring 59 is arranged between the disk 52 and the collar 58 and exerts upward pressure on the disk and, through the pins 51, on the collar 43. The tension of the spring 59 may be adjusted 85 by means of the nut 57..

A plurality of rods 60 are slidably arranged in the member 31 and have their lower ends in engagement with the knock-out collar 49. The upper ends of the rods 60 carry a bar 61 from which there projects a stud 62 which is adapted to engage with the bar 63 that is slidably mounted in the ram 29. Adjustable set screws 64 are mounted in lugs 65, on the guides 30, and are adapted to engage the bar 63 and arrest its movement on the upward stroke of the press. Springs 66 are connected with the bar 63 and normally tend to hold it 100 against the screws 64. On the downward stroke of the ram, the bar 63 is picked up thereby and carried along with it, the springs 66 being extended by this movement of the bar 63.

A stop-plate or stripper 67 is supported 105 above the die 45 by means of studs 68, for the purpose of disengaging the strip of stock 69 from the die 34 on the upward stroke of the latter. The proper position of the stock 69, in the press, is determined by a gauge member 70 which is secured on the base 36 by means of the screw 71. The gauge member 70 is engaged by the end 110 of the strip 69, and the fore-and-aft position of the strip is located by means of a guide pin 72.

As will be noted from the drawings, and particularly from Figs. 6 to 8, the clearance space 73 between the bore 46 of the die 34, 115 and the exterior surface of the male die 39, 120

is greater than the thickness of the stock from which the article is formed. It is common practice, in making stamping dies, to make this clearance space substantially equal 5 to the thickness of the stock, but, to carry out my invention, I make this clearance space at least double the thickness of the stock.

In practicing my improved method, the 10 strip of stock is placed in position, against the gauge 70 and the pin 72, when the dies are in the position shown in Fig. 1. The press is then tripped in the usual manner, the ram 29 descending and carrying with it 15 the die 34. When the lower end of the die 34 hits the stock it cooperates with the blanking die 45 to punch out the blank, the relative arrangement of these dies, at this instant, being as shown in Fig. 5. It will be 20 noted that the under surface of the blank is then in engagement with the upper end of the die 39, and the peripheral portion of the blank is clamped between the lower end of the die 34 and the collar 43 by the pressure 25 exerted by the spring 59. As the die 34 descends, the die 39 forces the blank into the bore 46, as shown in Fig. 6. The collar 43 descends with the die 34 and the spring 59 30 is thereby further compressed, thus increasing the upward pressure against the collar 43. As the peripheral portion of the blank is drawn into the bore 46, the area of the portion of the blank which is clamped between the die 34 and the collar 43 is gradually 35 reduced so that the clamping pressure, per square inch, on this area gradually increases, due not only to the decrease in the area of the clamped portion but also to the increase in the pressure exerted by the 40 spring 59.

During the drawing operation just referred to, the blank is drawn around the corner 47, of the die 34, and, as the clamping pressure on the peripheral portion of the blank increases, the work done upon the metal, in being drawn around the corner 47, materially increases and this work tends to harden the metal, as is well understood by those skilled in the art. The clamping pressure reaches its maximum just prior to the withdrawal of the periphery of the blank from between the end of the die 34 and the collar 43, this position being indicated in Fig. 7. Hence the metal adjacent the periphery of the blank will be subjected to the maximum amount of work, and will, therefore, harden to the greatest extent.

From Fig. 7, it will be seen that in this stage of the operation the article has an outwardly flaring end, and, on account of this end being very much hardened in the drawing operation, the subsequent drawing of this flanged end into the bore 46 will form a circumferential bend in the metal adjacent the base of the said flaring portion, as shown at

74 in Fig. 8. Thus the outwardly flaring flange that is in the blank, in the stage of the operation illustrated in Fig. 7, becomes the inward bead 24 seen in Fig. 9, the clearance 73 between the die members being sufficient to accommodate this bead. 70

From Fig. 7 it will be seen that the punch 41 is just about to engage the article, and, in Fig. 8, the punch 41 has cooperated with the bore 40 of the die 39 to punch out the central 75 portion of the end of the article.

On the upward stroke of the ram, the stock 69 engages the under-side of the stripper 67. The article will be carried up with the die 34 until the bar 63 engages the screws 64, 80 and then, upon engagement of the stud 62 with the bar 63, the collar 49 will be forced downwardly relative to the die 34 and knock the article out of the bore 46. At the same time, the spring 59 forces the collar 43 to its 85 upper position, as shown in Fig. 1.

In explanation of the drawings, it should be further stated that the dies, in Fig. 2, are shown in the same position as in Fig. 8, that is, at the completion of the down stroke of 90 the ram.

Having thus described my invention, I claim:

1. The herein described method of forming tubular metal parts with an internal bead 95 at one end which consists in forcing a metal blank into a hollow die having a rounded edge over which the metal of the blank is drawn, clamping the peripheral portion of the blank to increase the work done on the metal in drawing the periphery of the blank over the rounded edge of the die, releasing the clamping pressure when the edge of the blank reaches the curved edge of the die and then forcing the blank into the die sufficient- 100 ly to carry the edge of the blank beyond the curved edge of the die. 105

2. The herein described method of forming tubular metal parts with an internal bead which consists in pressing a sheet metal 110 blank into tubular form provided with an outwardly flaring flange at one end and at the same time so stressing the metal of said flange as to substantially harden it and then pressing said flange inwardly and forming a 115 circumferential bend in the part adjacent the base of said flange.

3. The herein described method of forming tubular metal parts with an internal bead at one end which consists in pressing a sheet 120 metal blank into tubular form provided with an outwardly flaring axially curved flange at one end and at the same time so stressing the metal of said flange as to substantially harden it and then subjecting said flange to 125 inward pressure throughout its circumference to form a circumferential bend in the part at the base of said flange and reduce the diameter of the edge of the flange.

4. The herein described method of form- 130

ing tubular metal parts with an internal bead at one end which consists in pressing a sheet metal blank into tubular form provided with an outwardly flaring axially curved flange at one end and at the same time so stressing the metal of said flange as to substantially harden it and then forcing the flange into an

opening having a smaller diameter than the edge of the flange and thereby forming an inward circumferential bend in the part adjacent the base of the flange.

In testimony whereof, I hereunto affix my signature.

HERMAN A. UNKE.
